WRIGHT DURYEA, OF GLEN COVE, NEW YORK.

Letters Patent No. 106,142, dated August 9, 1870.

IMPROVED ELECTRO-MAGNETIC LOW-WATER DETECTER FOR STEAM-BOILERS.

The Schedule referred to in these Letters Patent and making part of the same.

To all whom it may concern:

Be it known that I, WRIGHT DURYEA, of Glen Cove, in the county of Queens and State of New York, have invented a new and useful Improvement in Electro-magnetic Low-water Detecters or Alarms for Steam-Boilers, of which the following is a full, clear, and exact description, reference being had to the accompanying drawing forming part of this specification, and in which—

Figure 1 represents a vertical section of my improvement, as applied to a steam-boiler.

In carrying out this improvement, I propose to use any suitable apparatus through which an electro-magnetic may be made to give either an audible or visible alarm, but preferably one of sound, such, for instance, as the "calls" used in telegraph offices, or the so-called "fire-alarms," or "burglar-alarms," such apparatus being set in operation by making the fall of the water in the boiler, below the level determined upon for safety, act upon a circuit-closer in the electric circuit in which such electro-magnetic apparatus is placed.

This improvement relates more particularly to the manner and means through which the rise and fall of the water in boiler, or in a chamber or vessel in steam and water communication with the boiler, are made to open and close the circuit. The agency which I employ is the expansion and contraction of metals, by variations in temperature, at an opening provided in the electric circuit at some point within the boiler itself, or within some attachment thereto, in which the water-level varies as it does in the boiler.

The invention is capable of many modifications; but

To enable others to construct and apply it, I will proceed to describe that form which I consider the simplest or most preferable.

Referring to the accompanying drawing—

A is a metal pipe, arranged to extend any convenient height above the boiler, or proper water-level therein, outside of the boiler, and connected, in a steam-tight manner, with the boiler, by a screw-coupling, B, which serves, also, to secure or hold an extension pipe, A', that is open at its bottom, and descends to the level of the water determined upon for safety within the boiler.

These pipes A A' are virtually one, the upper section, A, of which carries, at or near its top, through a suitable screw-coupling or connection, C, and diaphragm or flange, D, impervious alike to steam and water, a tube, E, of glass, or other suitable material, arranged so as to be freely exposed, for a large portion of its length, to the space in the pipe A below the diaphragm D, and closed at its bottom.

Within this tube E, or pocket, as it may be termed, is a siphon-shaped tube, F, made of glass, or other suitable insulating material, and partly filled with quicksilver.

G G' are the end portion of the wires in the break of the circuit.

These wire termini pass through a suitable insulating filling or stopper, H, in the upper portion of the tube E, into the two legs, respectively, of the siphon tube, the shorter, and both legs of which, if necessary, are hermetically sealed.

The one G of said wires is, preferably, in constant contact with the quicksilver in the shorter leg of the siphon F, while the other wire, G', remains free from contact with the quicksilver in the longer leg of the siphon, excepting upon exposure of the pocket or tube E to steam heat, as produced by the filling of the pipe or pipes A A' with steam, from within the boiler, by the water falling below the level of the bottom end of the pipe-section A', when the increased temperature communicated to the quicksilver causes it to expand and establish contact with the wire G', which closes the circuit, and, by means of the apparatus hereinbefore referred to, causes the necessary alarm or signal to be made which indicates that the water has fallen below its proper level in the boiler. Said alarm or signal may be at any desired distance from the boiler.

When the water in the boiler rises above the lower end of the pipe-section A', the exposure of the pipe-section A to the air on the outside of the boiler will cause water to be forced, by the pressure of the steam in the boiler, up the pipe A A', and the temperature in the section A will be lowered, causing the quicksilver in the tube F to contract and free itself from contact with the wires G', thus breaking the circuit again.

If necessary, there may be a pet-cock or small leak connected with the pipe-section A, at or near its top, to provide for expulsion of the air contained in said section; or such pipe may be sufficiently long or elevated, and the tubes E and F be projected a sufficient distance down within said pipe, to dispense with such provision.

The same principle of action as herein described may be carried out with a solid metallic medium in the place of the quicksilver or fluid one, and, when quicksilver is used, it is not absolutely necessary that the tube containing it should be of siphon form, nor yet that the same should be surrounded by an outer tube, E; thus the opening and closing of the circuit may be provided for by means of a tube like that of a thermometer, partly filled with quicksilver, and the one of the wire's termini in the break of the circuit be inserted into the end of the tube which corresponds with the bulb of the thermometer, and with which the quicksilver is always in contact, while the other of the wire's termini is inserted in or through the opposite end of said tube, which should be so arranged at a suitable place in the boiler, or in some attachment at the proper level, that it will be exposed

to the action of water when the level is high enough, and to the action of steam when the level is too low, that the quicksilver will be so expanded, in the latter case, as to close the circuit, and so contracted, in the former case, as to open it.

A circuit-closer thus constructed may be arranged within or in connection with the glass or other water-gauge of the boiler.

What is here claimed, and desired to be secured by Letters Patent, is—

1. An expanding and contracting circuit-closer, arranged within a steam-boiler, or its connections, for operation, by the difference of temperature of the

steam and water therein, in connection with an electro-magnetic alarm or signal, substantially as and for the purpose herein set forth.

2. The combination of the wire termini G G' in the break of the circuit, the siphon tube F, containing quicksilver, the outer tube E, and the pipe or pipes A A', arranged for operation in connection with the boiler and with an electro-magnetic alarm or signal, substantially as specified.
